TIMING DEVICES

Harold L. Clark, Plantsville, Conn., assignor to The Sessions Clock Company, Forestville, Conn., a corporation of Connecticut

Application October 4, 1956, Serial No. 613,946

10 Claims. (Cl. 200—39)

This invention relates to timing and timing devices and especially to settable time-responsive mechanism for operating electric switches at predetermined times.

It is, of course, well known to operate switches for controlling electric circuits by time-responsive mechanism and a variety of forms of equipment have been devised for this purpose including elements readily and conveniently settable to a predetermined time at which time the circuits are automatically opened or closed. In some instances there are a plurality of settable controls so that it is possible to preset a time for circuit closing and then a later time for circuit opening or vice versa. Control of electric appliances such as radios, cooking equipment and the like can thus be rendered extremely convenient.

Heretofore timing devices which could satisfactorily operate electric switch means, and especially those capable of several sequential switching operations have involved mechanical complexity, the use of several sets of switch contacts, or other features, deemed at the time indispensable, which made the cost excessive and consequently barred or at least hindered their use for many purposes for which they would otherwise be found extremely convenient.

It is an object of the present invention to provide a timing device made up of few parts which can be produced in inexpensive fashion and which can be used to perform the same functions as devices much more complex and expensive in nature.

In particular it is an object of the invention to provide a timing mechanism requiring only a single electric switch for its operation and including simplified interconnections for turning the switch on or off at preset times.

A feature of the invention is the use of a contact assembly or switch whose contacts are continuously biased to one position, together with an operating lever therefor biased strongly enough to overcome the switch bias and to operate the switch, and time-responsive mechanism for controlling the movement of the lever in cooperation with its biasing means.

Another feature of the present invention is the operation of a single one-way-biased, circuit-controlling contact assembly by two time-responsive systems each having associated means including a biased lever affecting the contact assembly. One system serves to control the opening of the contacts and the other the closing.

It is also a feature of the invention to provide an arrangement in accordance with the immediately foregoing feature but in which the contact opening system also includes means for manually initially closing the contacts when the time for delayed opening is preset if no closing time is preset, thus avoiding the necessity for a separate contact closing operation which might be overlooked when used with equipment which does not provide an instantaneous obvious notification of the closed or open condition of the contacts.

Still another feature of the present invention is the operation of a contact assembly by a biased time controlled lever whose operation may be controlled either

directly from one settable time-responsive means or through an intermediate control element from a second time-responsive means.

A further feature of the invention is the provision of timing mechanism provided with "on" and "off" time setting assemblies each including a push button which may be pushed and rotated to preset the time period wherein the push buttons also constitute the sole means for operating the contact assembly manually to the "on" and "off" condition when no time period is present, i. e., when the indicator is set for present time or has a reading equal to the clock reading.

The present invention is an improvement on the device illustrated in the application of Fox and Clark, Serial No. 526,348, filed August 4, 1955, and has for another object the simplification of the control mechanism of said device.

Other objects, features and advantages will become apparent as the description proceeds.

In the drawings, 20 Fig. 1 is a front elevation of a timing mechanism according to the present invention;

Fig. 2 is an end elevation of the device looking from the right towards the left in Fig. 1, but with certain of the conventional clock motor gearing omitted for purposes of clarity;

Fig. 3 is a section taken on line 3—3 of Fig. 2;

Fig. 4 is a section taken on line 4—4 of Fig. 3;

Fig. 5 is a plan of the device of the invention as seen from the bottom in Fig. 10 but with certain parts of the mechanism shown in different position from that of Fig. 1;

Fig. 6 is a detail section on an enlarged scale taken substantially along line 6—6 of Fig. 3, with the parts in the Fig. 5 position;

Fig. 7 is a section similar to Fig. 6 but showing the parts in the position they would occupy in accordance with the showing in Fig. 1;

Fig. 8 is a fragmentary perspective of the switch levers and control means illustrating the parts in "off" position, looking in a direction substantially opposite to that of 40 Fig. 5;

Fig. 9 is a perspective view of the leaf spring control element of the invention;

Fig. 10 is a fragmentary detail elevation of the switch, levers and control means with the parts in the position shown in Fig. 8;

Fig. 11 is a fragmentary view, similar to Fig. 10, but in section along line 11—11 in Fig. 5, certain of the parts in the foreground being shown in phantom; and

50 Figs. 12, 13 and 14 are views similar to Fig. 10, but illustrating the parts in various positions, certain of the parts in the foreground again being shown in phantom.

Referring now to the drawings and particularly to Figs. 1 to 5, the timing mechanism of the present invention is illustrated as including a frame consisting of

55 a front plate 20 and rear plate 22 and suitable spacing posts 23. Mounted on the rear plate 22 is a synchronous motor 24 of conventional construction for driving the timing mechanism. A conventional clock driving train (not shown) is provided for driving a minute shaft 34 and an hour sleeve 28 from the synchronous motor 24

60 in a manner well known to the art. In Fig. 3 is illustrated in broken lines a gear 26, in this case the hour gear of the timing train, connected to and driven by the hour sleeve 28 to which is also connected an hour hand 30. The latter runs adjacent a clock dial 32 (see Fig. 1).

65 The hour gear and sleeve 26, 28 are supported by a minute sleeve or shaft 34 which carries at its end a minute hand 36 operating adjacent the same clock dial 32. The dial 32 is shown as carried by an escutcheon plate 38 supported by the front plate 20 of the frame. For convenience in setting the clock hands 30, 36, an extension 40 and a finger knob 42 may be provided on

the minute shaft 34. Affixed to the frame at a suitable location, for example against the rear surface of the front plate 20, is a contact assembly or switch 44. The switch 44 is a snap switch and is shown as including an actuator 46 which is biased to extended position, and soldering lugs 44a. The extended position of the actuator 46, it will be understood, may be either an open or closed position of the contacts in the switch 44, but for the purposes of this description it will be assumed that the extended position of actuator 46 is associated with an open switch or "off" condition, and that when the actuator 46 is pressed and held in against its biasing force the switch contacts will be closed or in "on" position. Movement of the actuator 46 in either direction is termed "actuation" thereof, while the position away from which it is normally biased will be considered hereinafter as being the "operated" position.

Proceeding now to the means for controlling the action of the switch 44, the gear 26 is shown as driving idlers 48 and 48a which drive timing gears 50 and 50a respectively. For this purpose, the gear 26 may be the gear which drives the hour sleeve 28 or any other suitable gear in the mechanism which rotates at a convenient rate, for example, once in every twelve hours. The ratios of the gear teeth in gear 26 and gears 50, 50a are preferably such that the gears 50, 50a will make one revolution every 24 hours. Mounted adjacent each of the gears 50, 50a are time setting wheels 52, 52a respectively. Inasmuch as the time-responsive means or assemblies at either end of the frame are very similar in structure, the description herein will proceed on the basis of the detailed features of one only of the assemblies with the understanding that in the absence of any distinctions made herein the parts of the other assembly are the same as the one described. For purposes of convenience the time-responsive assembly at the right hand end of the frame in Figs. 3 and 5 will be designated the "on" assembly 47 and that at the left hand end the "off" assembly 47a. The description will proceed primarily on the basis of a detailed description of the "on" assembly 47, the corresponding parts of the "off" assembly being designated by the same reference numerals with the postscript "a" attached.

Timing gear 50 and time setting wheel 52 are provided with axially engageable and disengageable clutch means, for example the lugs 54 and the matching openings 56, as seen more clearly in Figs. 6 and 7. While a single lug and socket or opening would provide an operative structure, the reasons for the use of a plurality of each are presented in the aforesaid copending application. The timing gear 50 is shown as integral with the sleeve 58 and is rotatably mounted on a time setting shaft 60. The gear 50 and shaft 60 are also relatively slidable to a limited extent. Affixed to the shaft 60 is an abutment washer 61 by which the gear 50 can be axially moved away from wheel 52 when the shaft 60 is pushed inwardly. The time setting wheel 52, however, has a free sliding noncircular driving connection with the shaft as indicated by reference character 62 so as to be slidable relative thereto but constrained to rotate therewith at all times. A central hub 64 of the wheel 52 extends through and is rotatable in an opening 66 in the front plate 20. Hub 64 has a bearing fit in opening 66 and shaft 60 has a rotatable and slidible bearing fit in a suitable opening 67 in the rear plate 22. These two bearing arrangements serve as the mounting for the time responsive assembly 47 on the frame of the timer. The general axial position of the assembly is determined essentially by the location of the hub 64 which is held in position in the opening 66 by a suitable retainer flange 68. A compression spring 70 surrounds the sleeve 58 and abuts against the back plate 22 so as to urge the gear 50 towards the setting wheel 52 at all times, and to urge the lugs 54 into the openings 56 when-

ever the gear 50 and wheel 52 are properly oriented with respect to one another.

The time setting shaft 60 may be slid through the gear 52 by manually pushing on an extension 72 having a manually accessible operator or finger knob 74, so as to cause the washer 61 to separate the gear 50 axially from the wheel 52 against the force of spring 70. The shaft 60 may then be rotated to remove the openings 56 from registry with the lugs 54 so that the gear 50 and wheel 52 will remain axially separated until the timing gear has been rotated by gear 48 through an angle sufficient to restore registry of lugs 54 and openings 56. The degree of inward travel of shaft 60 may be determined in any suitable manner. For instance, the engagement of a conical portion 186 of the shaft 60 in a conical stop recess 167 in hub 64 may serve this purpose. The range of displacement of gear 50 and the thickness of its driving gear 48 are such that their meshed relationship is maintained at all times as can be seen from Figs. 6 and 7. The time setting wheel conveniently carries a dial 76 having time indicia 78 (Fig. 1) which will normally be visible through a suitable opening 80 in escutcheon plate 38, to indicate the time of day at which the axial motion of gear 50, occasioned by the entrance of lugs 54 into openings 56, will occur.

It will be noted that the time setting wheel 52 has on its face adjacent plate 20, a peripheral frictional bearing element 82 which rides against front plate 20 under the influence of spring 58 and serves to maintain the wheel in any desired set position until such time as the lugs 54 and openings 56 align and become interengaged, whereupon the wheel 52 is positively driven by the gear 50.

The axial motion of gear 50 is arranged to generate the displacement required to actuate switch 44, and the displacement is transmitted to the switch by an "on" actuating member or lever 100 which combines with the time-responsive assembly 47 to form an "on" timing means for the switch 44. The lever 100 has an opening 102 (see Fig. 3) at an intermediate point in its length loosely receiving the sleeve 58 with the lever arranged between gear 50 and the end of spring 70. Preferably dimples or other rounded local projections 104 are formed on lever 100 to provide a member suitably localizing its bearing against gear 50 for easy rocking motion. One end of the lever has a free rocking connection with the plate 20, and the other end 108 is positioned to travel in a path where it will strike the actuator 46 of switch 44. The free rocking connection takes the form of a bent-up, notched tongue 106 at the end of lever 100, loosely engaged in a T-slot 107 in plate 20, as best seen in Fig. 4, although any suitable pivotal mounting may be substituted for this arrangement. Thus it can be seen that when the end 108 of the lever 100 moves towards front plate 20 due to the action of spring 70, actuator 46 is operated or depressed to close switch 44. When, however, the gear 50 of timing assembly 47 moves the lever 100 and its end 108 away from front plate 20, to set position as in Fig. 7, the actuator 46 is released and allowed to return to normal switch open position.

With particular reference to Figs. 8 and 9, there is also provided a control means 120 whose action cooperates with that of the spring 58 and gear 50 in controlling the positioning of end 108 of lever 100. The control means or member 120 comprises an arm which in the specific embodiment here shown takes the form of a leaf spring 122 mounted on the front plate 20 and projecting rearwardly adjacent the end 108 of lever 100. One convenient method for mounting the same is to provide a bent tab 124 having an opening 126 which may be used to hold the control means 120 by clamping the tab between the switch 44 and the front plate 20 and passing one of the mounting fasteners for the switch through said opening 126. The upper end of the leaf spring is normally

biased to the right, as viewed in Fig. 10, and carries an operating member 128 for cooperation with the lever 100 in a manner which will presently appear. The operating member 128 is preferably formed as a tab integral with and merely bent from the material of the leaf spring 122, and is given a V-shape to provide oppositely sloping cam surfaces 130 and 132. For cooperation with the leaf spring, the free end 108 of lever 100 is bent up from the plane of the lever to form a cam portion 134 extending in the direction of pivotal movement. This cam portion or tongue is formed to provide a V-notch in the edge adjacent spring 122. This notch provides oppositely sloping cam surfaces 136 and 138 for cooperation with the cam surface of the operating member 128. The operating member 128 has two positions one being its innermost or preventing or blocking position under the influence of leaf spring 122; the other being its outer non-blocking or on-permitting position when the leaf spring is deflected outwardly as will be described presently. Normally when the member 128 is urged inwardly to blocking position by the leaf spring 122, its cam surface 130 reacts against cam surface 136 of tongue 134 and cams the same in a direction such that lever end 108 is withdrawn from and held away from switch 44, and the switch operator 46 is permitted to move to its "off" position as seen in Figs. 8 and 10. The leaf spring 122 has sufficient force to accomplish this even against the effect of spring 70 due to the leverage arrangement. Thus the operating member 128 has the primary function of blocking the "on" movement of lever 100, or of moving it to "off" position when it is "on".

Whenever the lever 100 is forced away from front plate 20 as by gear 50 (see Fig. 12), the cam surface 138 of its tongue 134 reacts against cam surface 132 on operating member 128 and cams the leaf spring to non-blocking position. The control means 120 thereupon becomes latched in this position in a manner to be herein-after described, and, if not otherwise prevented, the end 108 of lever 100 will move under influence of the spring 70 to the Fig. 12 position, wherein the switch actuator 46 has been moved by the lever end 108 to "on" position.

It will be noted that the tongue 134 has a guide edge 140 designed to run against a fixed guiding surface, furnished for example by a tab 142 bent inwardly from the rear plate 22. This arrangement supports the lever end against the side thrust of leaf spring 122 and guides the lever for free oscillating movement about its rockable mounting 106, 107.

In order to operate the switch 44 from the time-responsive assembly 47a (which is substantially identical with assembly 47 as explained heretofore), an "off" actuating member or lever 150 is provided which combines with the time-responsive assembly 47a and the control means 120 to provide an "off" timing means. The lever 150 has an opening 152 at an intermediate point in its length loosely receiving the sleeve 58a with the lever arranged between gear 50a and the end of spring 70a. The lever 150 is also preferably provided with dimples or round local projections 154 similar to projections 104 on lever 100 and for the same purpose. One end of the lever has a free rocking connection on plate 20 and the other end 158 is positioned adjacent the control means 120 and is provided with a bent-up tongue or cam portion 160 for interaction with an operating latch member 162 taking the form of a tab on leaf spring 122. Tongue 160 is thus disposed in juxtaposition to cam portion 134 of lever 100 and extends parallel thereto. The free rocking connection of lever 150 on plate 20 is the same as that of its counterpart, lever 100. As in the case of lever 100 also, the tongue 160 of lever 150 has a guide edge 164 which bears against the surface of guide tab 142 on rear plate 22 under the urging of leaf spring 122.

Tongue 160 of lever 150 has a notch in its edge adjacent the latch member or tab 162 of leaf spring 122. The lower portion of this notch, as seen in Fig. 10, slopes

inwardly to provide a cam surface 166 corresponding generally with the cam surface 138 of tongue 134 and adapted to interact with an extension of surface 132 on leaf spring 122. The upper edge of the notch in tongue 160 is substantially perpendicular to the left hand edge of the tongue and provides a latching abutment 168 against which the tab 162 of leaf spring 122 may engage.

One function of the "off" lever 150, therefore, as seen in Fig. 10, is to latch the control means in a condition preventing lever 100 from actuating switch 44 to "on" position. This is done by allowing the operating member 128 of leaf spring 122 to move, under the urging of the leaf spring, into the V-notch in tab 134. In this condition, the operating end 108 of lever 100 is held out of operating engagement with plunger 46 of the switch. If, however, the lever 150 is raised against the force of spring 70a by gear 50a, thereby at the same time camming leaf spring 122 to the left as seen in Fig. 12 by interaction of cam surfaces 132, 166 of the leaf spring and tongue 160, respectively, lever 100 is free to move toward switch 44 and actuate plunger 46 to its operated position. This movement is provided by spring 70 acting against lever 100.

Another function of the lever 150 is to latch the leaf spring 122 in the position shown in Fig. 13 so that lever 100 is free to operate the switch. This condition is brought about by raising lever 100 so that interaction between surfaces 132, 138 of the leaf spring and tongue 134, respectively, cams the spring sufficiently to the left (as viewed in Fig. 13) to disengage latching tab 162 from latching abutment 168, allowing lever 150 to move toward front plate 20, under the urging of spring 70a, until tab 162 rests on the outer edge 170 of abutment 168. Upon the return of lever 100 towards front plate 20, the operating member 128 of leaf spring 122 can no longer engage the notch in tongue 134, and the "on" lever 100 therefore is free to travel to a position in which switch 44 is actuated to "on" condition. This condition is illustrated in Fig. 14.

From the foregoing description it will be plain that the control means 120 has two positions, namely (1) an "off" position (to which it is normally biased by its own resilience) in which it prevents operation of the switch actuator 46 and (2) an "on permitting" position (in which it may be latched on either side of the notch in tongue 160 by latch element 162) in which such prevention is removed and the "on" or "off" condition of the switch actuator 46 is determinable by the position of gear 50 through lever 100. The several ways in which the timer device can be operated, whereby to bring about the various conditions just mentioned, will now be described.

Automatic operation

In order to preset a time for a turning on operation of the switch 44, the operator will push the "on" knob 74 to disengage lugs 54 from openings 56, and rotate the knob to remove the lugs 54 from alignment with openings 56, whereby the gear 50 and wheel 52 are maintained in spaced relationship and the lever 100 is held in "off" position until the timing train returns the lugs 54 and openings 56 to registering position. The setting rotation of the knob by the operator is, of course, continued until there appears in opening 78 the clock time at which it is desired to have switch 44 close. The pushing in of the knob 74 causes the latching tab 162 to latch the control means 120 in "on permitting" position and, together with the rotation of the knob, places the parts generally in the position of Figs. 7 and 14 (except that in Fig. 14 the lever 100 would be raised instead of lowered as shown, and switch actuator 46 would consequently be in "off" position until the preset time period has elapsed and lugs 54 are realigned with holes 56). If no particular predetermined "off" time is required, the parts will remain in the stated position until

the preset "on" time has been reached, whereupon the lugs 54 will drop into openings 56, permitting lever 100 to operate the actuator 46 and close the switch, which will then remain closed indefinitely.

If it is also desired to preset a time for subsequently opening switch 44, the operator, in addition to the above described operation, will also push the "off" knob or manually accessible operator 74a to disengage the corresponding lugs and openings (not shown) of the time-responsive assembly 47a. He will then rotate the knob until there appears in opening 78a the clock time at which it is desired to have switch 44 open again. Then the time will run as aforesaid until the predetermined closing of the switch 44 has occurred, whereupon the parts will appear as shown in Fig. 12. The time will continue to run until the lugs and openings of the time-responsive assembly 47a are in register, when the lugs will drop into the openings permitting lever 150 to lower until tab 162 drops into the notch in tongue 160 and is engaged against abutment 168. In the course of this action, cam surface 139 on the leaf spring acts against cooperating surface 136 on tongue 134, raising the end 108 of arm 109 to lift it away from actuator 46 and open the switch as seen in Fig. 10.

In some instances it may be desired to close the switch immediately, and merely arrange for a preset time for the switch to open automatically. In this situation, there is no need to perform any operation with the "on" button to close the switch, for the cam portion 166 of tongue 160 will perform this function when the button 74a is pushed to make the "off" time setting as previously described.

From the foregoing it will be appreciated that a very convenient arrangement is provided for making time settings for individual automatic "on" or "off" operations, when either one is desired without the other. Each of the knobs 74, 74a will set its own initial switch condition under such circumstances, provided only that the other knob is arranged for no preset time interval.

The reason for this will be apparent when it is noted that each shaft 60 or 60a normally brings about a different switch condition at the opposite ends of its reciprocatory travel. In other words the "on" shaft 60, when extended, produces an "on" condition of the switch 44, and when pushed in produces an "off" condition of the switch (i.e. a condition opposite to its own designation). Likewise the "off" shaft 60a, when extended, produces normally an "off" condition of switch 44 as in Fig. 10, but when pushed inwardly it normally produces an "on" condition of the switch as in Fig. 12 (again a condition opposite to the shaft designation). Thus each control incorporates the essential features for an individual setting and avoids the necessity for the extra step of somehow turning the switch to the preliminary "on" or "off" condition in connection with the presetting of an "off" or "on" automatically timed switch operation. It is thus very unlikely that the initial switch condition will be overlooked, as would be possible with prior timers where the circuit included a slow acting device which did not at once attract attention to its condition, e.g. an electric heating element or a radiation receiving set whose elements have a warm-up period before an audible or visible signal is experienced by the operator.

Manual operation

When the operator desires merely to operate the device to presently open or close the switch without any intervening preset time interval, he can accomplish the same in a very simple and uncomplicated fashion with the device of this invention. Assuming that no preset time period is running, of course, and that the lugs 54 are in openings 56 (and the corresponding lugs and opening of assembly 47a are in mesh), all that is required is for the operator to push and then release the knob bearing the designation corresponding to the type of switch actuation desired. Thus, if he pushes the "on" button 74, lever 75

100 will be raised and leaf switch 122 cammed to release tab 162 from beneath abutment 168 to the position shown in Fig. 13, latching the control means 120 in that position so that it cannot interfere with tongue 134. Then when 5 pressure on knob 74 is relaxed, the lugs 54 re-enter the openings 56 allowing lever 100 to lower so that its end strikes actuator 46 closing the switch and holding it closed as shown in Fig. 14. If the operator pushes the "off" knob 74a he raises lever 150, releases the control means 10 120 from the Fig. 14 position and allows it to move to the Fig. 10 position, causing the leaf spring to cam lever 100 upwardly and release the actuator 46. This operation can take place without fully disengaging the lugs from the respective openings in the time-responsive assembly 47a.

It can be seen from the immediately foregoing description that the problem of selecting between automatic and manual operation is made easy of solution for the operator, for the same control elements, namely knobs 74, 20 74a, are used in a simple fashion in either case, and no conversion setting of a separate element to condition the mechanism for one type of operation or the other is required. This simplicity of operation is also achieved, furthermore, without rendering the mechanism more complex, and in fact simplifying it in many respects as compared with other timers of generally analogous function. If an automatic time setting is in effect and it is desired to render the same nugatory and to change to manual operation, it is necessary only to rotate the knobs 74, 74a, until the lugs of the timing assemblies 47, 47a, are in each case received in the corresponding openings, whereupon the device is ready for manual operation.

So that it will be possible for the operator to tell at a glance whether (1) a time period has been set or (2) the device is in condition for manual operation, mechanism may be provided for closing the windows 89 or 80a to obscure the dial 76 or 76a whenever the corresponding knob 74 or 74a has no time setting and is free for manual operation. This mechanism is the same as that described in the aforesaid co-pending application of Fox and Clark, Ser. No. 526,348, to which reference is made for a detailed description of the construction and operation of that mechanism.

The invention may be carried out in other specific ways than those herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

What is claimed is:

1. In a timer device for an electrical appliance, a frame member, a switch mounted on said frame member and having a contact assembly operable between open and closed circuit positions and normally biased to one of said positions; actuating means for said switch comprising a lever pivotally supported on said frame member and normally biased to overcome the bias of said contact assembly and move it to an operated position, said lever being formed at a free end to provide a cam portion extending in the direction of pivotal movement; a clock mechanism; settable time-responsive means driven by said clock mechanism and engageable with said lever for overcoming its bias and holding the lever in non-operating position until a pre-set time period has expired; control means independent of said time-responsive means for controlling the position of said lever, said control means comprising an arm resiliently mounted on said frame and having a free end projecting into engagement with the free end of said lever, said arm being movable between a blocking position, in which it engages the cam portion of said lever and prevents movement of said contact assembly to operated position by said lever, and a nonblocking position, said arm being normally biased to

blocking position; and latch means for latching said arm in nonblocking position.

2. A timer device as defined in claim 1, wherein the cam portion of said lever has a cam surface, and said arm has a complementary cam surface, which surfaces engage upon moving said lever manually against its bias to move said arm to, and latch it in, said nonblocking position.

3. A timer device as defined in claim 2, wherein the cam portion of said lever is provided by a V-notch formed in said lever and said complementary cam surface on said arm is formed by a V-shaped operating member on the latter.

4. In a timer device for an electrical appliance, a frame member, a switch mounted on said member and having a contact assembly operable between open and closed circuit positions and normally biased to one of said positions; switch actuating means comprising a lever pivotally secured to said member and biased to overcome the bias of said contact assembly and move it to an operated position; means engageable with said lever to move it out of its normally biased position comprising a set of axially separable, rotatable clutch members having a registering position in which they are locked together against relative rotation but which are capable of relative rotation when axially separated, said clutch members in nonregistering positions blocking said lever to prevent its movement of said contact assembly to said operated position; clock mechanism, and means for driving one of said clutch members from said mechanism whereby said one clutch member is rotated relative to the other until registration between them occurs; a control member comprising a leaf spring biased normally to engage the free end of said lever and prevent movement of said contact assembly to said operated position independently of said clutch members; and means for latching said leaf spring out of blocking position.

5. In a timer device for controlling the operation of an electrical appliance, a switch for opening and closing an electrical circuit and operable between actuated and unactuated positions, means normally biasing said switch to its unactuated position, and a plunger for moving said switch to its actuated position; a frame on which said switch is supported; control means for actuating said switch including a pair of levers, each of which is pivotally supported at one of its ends upon said frame and has a free end extending into juxtaposition with the free end of the other, said free ends being formed to extend substantially parallel to each other in the direction of pivotal movement of said levers; resilient means normally urging each of said levers in a given direction about its respective pivot axis, and manually settable time-responsive means for moving each of said levers in the opposite direction against said resilient means; a clock mechanism for controlling said time-responsive means; a leaf spring supported on said frame and having a free end projecting parallel to the adjacent free ends of said levers and in resilient contact with them; said spring having camming surfaces formed on it and each of said lever free ends being formed to provide cooperating camming surfaces engaged, respectively, by said spring surfaces; one of said levers being engageable with said switch plunger and being urged by its resilient means to overcome said normal switch bias and move the switch to its actuated position, said one lever being resiliently restrained against such movement by engagement of the camming surface of its free end with the cooperating camming surface of said leaf spring; the camming surface of said other lever reacting with the respective surface of said spring, when said other lever is moved against its normal bias, to cam said spring away from said one lever, whereby the latter is freed to contact said plunger and move said switch to its actuated position.

5 6. A timer device as defined in claim 5, wherein said other lever is formed at its free end to provide a latching abutment and said spring is formed to provide a cooperating tab, said tab being engageable behind said abutment to prevent full travel of said other lever toward said given direction.

10 7. A timer as defined in claim 6, wherein said spring tab is disengaged from behind said abutment upon movement of said spring away from its normally biased position and said other lever is then freed to travel to the full position in said given direction.

15 8. A timer device as defined in claim 7, wherein said latching abutment is formed to provide an outer edge upon which said spring tab is adapted to rest in the full position of said other lever, whereby said spring is latched in a position permitting said one lever to move said switch to its actuated position.

20 9. A timer device as defined in claim 6, wherein said cam surface and latching abutment of said other lever are provided by a notch formed in said other lever, said time-responsive means being manually operable to displace said other lever against said resilient means and settable to retain said other lever in such displaced position for a selected period of time whereby said spring is latched in a position permitting said one lever to move said switch to its actuated position during such period of time.

25 10. In a timer device for an electrical appliance, a frame, a switch contact assembly on said frame having open and closed circuit positions and normally biased to one of said positions; means for actuating said contact assembly including a first lever pivotally supported on said frame and normally biased to overcome the bias of said contact assembly and to move it to an operated position, said lever being formed to provide a free end having

30 a cam portion extending in the direction of pivotal movement of said lever; a second lever pivotally supported on said frame and likewise formed to provide a free end having a cam portion, said latter portion being in juxtaposition with that of said first lever and generally parallel thereto, said second lever being normally biased in the same direction as the first; first and second sets of time-responsive means engaging said first and second levers, respectively, each set comprising axially separable clutch members, one of which engages its respective lever and moves it out of normal biased position when said clutch members are axially separated, said members being rotatable relative to each other when axially separated and having registering means maintaining axial separation thereof except in a predetermined rotated position; means

35 for manually separating said clutch members axially and effecting relative rotation between them to maintain them out of registering position; and clock mechanism driving one of said members to return it to registering position with the other; detent means comprising an arm resiliently

40 mounted on said frame and having a free end projecting into yielding engagement with the cam portions of the free ends of said levers and normally blocking said first lever to prevent it from moving said contact assembly to said operated position; said cam portion on said second lever being operable, upon actuation of said second lever by separation of its clutch members, to move said arm out of blocking engagement with respect to said first lever, whereby the latter is freed to move said contact assembly to said operated position.
